RESTAURANT BUILDING

John S. Neumeyer, Gretna, La., assignor to Captain Space
Burger Corporation, Gretna, La., a corporation of Louisiana

Filed July 16, 1969, Ser. No. 18,222

Term of patent 14 years

Int. Cl. D25—04

U.S. Cl. D13—1

I claim:

The ornamental design for a restaurant building, substantially as shown and described.
